CURTAIN ROD GUIDE

William A. Murray, Ajo, and Gordon T. Alley,
Tucson, Ariz.

Application February 24, 1947, Serial No. 730,320

1 Claim. (Cl. 223—105)

1

This invention relates to improvements in curtain rod guides or devices adapted for attachment to curtain rods for facilitating the threading of the curtain rod through the hem of a curtain or the like.

Heretofore, guides or other attachments for this purpose have been rigidly secured to the curtain rod. We have discovered, however, that if the guide is loosely mounted on the curtain rod so that it tends to oscillate with respect to the rod, the rod may be threaded through the hem much more easily, with greater rapidity and with less tendency to tear the hems of even the flimsiest of materials.

It is an object of the present invention, therefore, to provide a curtain rod guide so constructed and arranged that it is capable of slight movement laterally of the rod to which it is attached and, in general, to provide an improved curtain rod threading device.

It is a further object of the invention to provide a device which is extremely simple in construction and durable and efficient in operation.

Other and further objects and advantages of the present invention will be apparent from the accompanying drawings wherein a preferred embodiment of the principles of the invention has been selected for exemplification.

In the drawings:

Fig. 1 is a side elevational view of a curtain rod guide constructed in accordance with the present invention;

Fig. 2 is a side elevational view of the device of Fig. 1 positioned in a curtain rod of the usual kind, channel-shaped in cross-section;

Fig. 3 is a longitudinal sectional view through Fig. 1 and Fig. 4 is a plan view of the device shown in Fig. 1 with the guide head partly broken away and indicating in dotted lines the preferred extent of the oscillatory movement of the head.

In the drawings, wherein like numerals refer to like parts, guide head 10 which may be formed of any suitable material such as metal, wood or plastic is provided in any configuration and contour, such as the tapered shape, as shown. Opening rearwardly of the head 10 are a pair of sockets or recesses 12 and 14, preferably outwardly diverging. Curtain rod fastening means 16, which may be a spring wire bent into elongated elliptical shape adapted to fit snugly in a channel-shaped curtain rod, is provided with integral outwardly bent fingers 18 and 20 for engaging the sockets or recesses 12 and 14, respectively, whereby to secure the attaching means 16 to the guide head 10.

2

As shown, the sockets or recesses 12 and 14 are somewhat greater in cross-sectional area than the fingers 18 and 20 so that the rocking movement of the enlarged sockets with respect to the

5 fingers will enable the head 10 to oscillate with respect to the attaching means and the curtain rod to which it is secured, but at the same time to be secured against separation from or longitudinal movement relative to the clip means 16.

10 Attaching member 16 can be readily snapped into or out of engagement with the sockets or recesses of the guide head. Thus, the same guide head may be used with interchangeable attaching means adapted to fit a variety of curtain rods of different shapes and sizes.

15 In use the attaching member 16 is intended to be inserted in an end of the curtain rod to seat rigidly therein with the guide head 10 projecting from the rod and so supported that it is capable of oscillatory or lateral movement in either direction relative to the rod. In this manner the head 10 acts as a flexible guide very readily and rapidly to thread the curtain rod through the hem of a curtain or other hanging of any material,

20 whether starched or not.

25 When threading is completed the guide is merely pulled from the end of the curtain rod and is ready for insertion in another curtain rod for another threading operation.

30 We wish it to be understood that the invention is not limited to the precise construction set forth but that it includes within its purview whatever changes fairly come within either the terms or

25 the spirit of the appended claim.

35 Having described our invention, we claim:

A guide for threading a curtain rod comprising, a guide head, a plurality of angularly disposed sockets opening at the rear of said guide head, a spring wire clip for attaching said guide head to a curtain rod and angularly disposed fingers carried by said clip and loosely fitting in said sockets whereby to support said guide for lateral movement with respect to the curtain rod.

40 WILLIAM A. MURRAY.
GORDON T. ALLEY.
